ELECTRIC HEATER

Gustav Fredrickson, Bristol, Conn., assignor, by
mesne assignments, to General Motors Corporation,
Detroit, Mich., a corporation of Delaware

Application July 11, 1931, Serial No. 550,137

16 Claims. (Cl. 219—13)

The invention relates to electric heaters and comprises all of the features of novelty herein disclosed. An object of the invention is to provide an improved heater using alternating magnetism as a source of heat to give rapid controllable heat of uniform penetration in the work to be heated. Another object is to provide a magnetic gap induction heater of high efficiency. Another object is to provide an all-metal heater having a self-forming lining and improved cooling features. Still another object is to provide a heater having low voltage inductors of single turn loops and a generally compact and simplified, low-cost construction. Yet another object is to provide an induction heater capable of feeding work directly to a forging machine or the like.

To these ends and to improve generally upon devices of this character, the invention consists in the various matters hereinafter described and claimed. In its broader aspects, the invention is not necessarily limited to the specific construction selected for illustrative purposes in the accompanying drawings in which

Fig. 1 is a perspective view of the heater with some parts broken away and others in section.

Fig. 2 is a diagram.

Fig. 3 is a sectional view of a portion of Fig. 1 to a large scale.

Fig. 4 is a side elevation.

Fig. 5 is a front view.

Fig. 6 is a perspective view of the inductor.

Fig. 7 is a sectional view on line 7—7 of Fig. 6. The numerals 10 and 12 indicate two sets of laminations of ferrous material separated by spacing plates 14 and all clamped together between end plates 16 by nuts on the threaded ends of tie-bars 18. Each set of laminations is conveniently formed in upper and lower E-shaped sections, alternate pairs of plates meeting at the lines 20 as indicated in Fig. 5 and the intervening pairs meeting at the lines 22 to break joints. The laminations enclose a generally rectangular space but have central core projections 24 extending towards one another and preferably terminating in arcuate ends leaving a gap to conform approximately to work of circular cross section.

Extending lengthwise in the space between the laminations is an inductor having straight side walls 26 and 28, the side wall 28 preferably being in two aligned sections. Both side walls have adjacent extensions 30 presenting opposed arcuate surfaces leaving a space for the work. Each side wall 28 is rigidly connected at one end to

an end of the side wall 26 by an integral cross piece 32. The side walls are hollow to form passages 34 for cooling fluid and the cross pieces 32 are likewise hollow to form connecting passages 36. See Fig. 7.

The side wall 26 is united as by brazing, to an upright hollow leg 38 and the adjacent ends of the side walls 28 are similarly united to upright hollow legs 40 and 41. The upper ends of the legs 38 and 40 are united to a hollow loop member 42 and the lower ends of the legs 38 and 41 are united to a hollow loop member 44. Cooling fluid, such as water, is admitted (Fig. 6) to the loop member 42 through a supply pipe 46, the fluid first traversing the loop, then descending the hollow leg 40 to the passage 34 in one of the hollow side walls 28, crossing through the passage 36 to the hollow side wall 26, and finally going out through the pipe 48. Similarly, a pipe 50 supplies cooling fluid to the lower loop 44 and a pipe 52 carries the fluid away. The hollow nature of the foregoing parts is shown in Figs. 5 and 7 while Fig. 6 indicates the course of flow by arrows. The side walls, loops and connecting legs are preferably composed of copper.

The loop members 42 and 44 form the secondaries of transformers 54 and 56 the magnetic fields of the transformers being carried by ferrous metal either in the form of wire or of laminations similar to the laminations 10. A layer 30 of insulation 57 (Fig. 3) lines the interior of each field and encloses the loop member 42 or 44 and its primary coil, the primary coil 60 or 62 being further insulated by a layer of insulation 58. The coil 60 or 62 is preferably composed of a continuous winding of copper tubing surrounded by an insulating tube 63. The hollow tubing not only carries an electric current but also carries a current of cooling fluid, such as water, admitted through a supply pipe 64 to a branch coupling 66. A branch pipe 68 conducts the cooling fluid to the lower part of the coil 60 while a pipe 70 carries the fluid away. The couplings for the pipes are conveniently supported by a shelf 72. A branch pipe 74 conducts the cooling fluid to the middle portion of the coil 62. A pipe 76 conducts the fluid away from the upper portion of coil 62 while a pipe 78 conducts the fluid away from the lower portion. Electric current from a three-phase, three-wire generator is conducted by the pipes to the tubing of the primary coils and the fields link the primaries with the secondaries to produce therein an alternating low voltage current. One lead wire 80 is connected to the coupling of the pipe 70 below the shelf 72,

another wire 82 is connected to the coupling of the pipe 76 and the third wire 84 is connected to the coupling of the pipe 78.

The heater is supported in any convenient way, as by channel iron standards 90 carrying angle irons 92 bolted to the tie-bars 18. Horizontal channel irons 94 and 96 connect the standards, and angle irons 98 support the shelf 72.

The shape of the air gap between the core 10 projections 24, 24 may be varied to suit the work W which, in the illustrated construction, is a bar of steel of circular cross section fed endwise into the guide. An alternating magnetic field of intense magnetic flux density is set up 15 in the gap, the cold steel bar, or any other material of high magnetic permeability, initially being a part of the core. Due to hysteresis and eddy currents, the bar heats until a temperature is reached where its permeability to magnetism 20 is reduced. As a result of decreasing permeability, the magnetic flux density decreases, thus causing decreased energy input to the work as its temperature rises. In other words, the work absorbs greatest energy while cold and the supply of energy diminishes progressively as it is heated. The ultimate temperature is reached 25 when the energy input decreases to the value of radiated heat plus the heat conducted from the work to the surrounding walls. This automatic control of the ultimate temperature by the decreasing flux density is an important feature.

Heating of the work occurs internally, rather than from the outside as in ordinary furnaces, and is very rapid. When cold, the steel bar acts 30 both as a secondary to a transformer (having the field 10 or 12) and as part of a core but, when it is heated, it acts only as a secondary. The bar is also self feeding endwise in the guide because, as the foremost end heats and loses its 35 magnetism, the following portions of the bar which are still magnetic are drawn forward like the core of a solenoid until they too lose their magnetism. The inductor 26, 28 is preferably made of copper or other conductor that will oxidize and so form a lining of poor electrical conductivity at the gap, thereby preventing burning of the bar by direct contact at 30. The heater can thus be built entirely of metal without necessity for a special lining. Also, the water 40 jackets 34 have some cooling effect on the core projections 24 so that wear on the latter by contact of cold metal with hot is minimized. The construction is further simplified by using low voltage inductors of single turn loops, such as 26, 45 32, 28, about the work. Inasmuch as the work is initially part of a core and then acts as a secondary to a transformer, the heater is to be distinguished from a so-called coreless furnace and from a core type induction furnace and may be 50 termed a magnetic gap induction heater. The shape of the gap will vary with the shape of the work but is such as to give minimum distance between the core projections 24, 24 with maximum area therebetween. Thus the flatter the 55 bar, the closer the projections 24, 24 will be made to approach one another. The current value required for inducing intense magnetism is thus reduced to a minimum with a resulting high power factor and efficiency, and the efficiency becomes 60 more pronounced when the metal is a thin sheet with the gap shaped to conform to it.

All non-magnetic materials act as a secondary to a transformer when placed in the air gap and are heated to a temperature dependent on the 65 current supplied to the transformers and on the

electrical resistance. The magnetic field remains constant under constant current conditions.

It will be noted that the apparatus herein shown comprises two heaters combined in one and energized from the primary coils 60 and 62. The Scott or T-connector produces two single phases controlling one heater and this balances the load on a three-phase, three-wire generator. The heated bar may be led from the heater directly to a forging or heading machine which shapes and cuts off the foremost end as fast as the bar advances. The low voltage at the inductor is an important safeguard in operating the machine.

I claim:

1. In an induction heater, a pair of straight side walls spaced apart to embrace and guide a piece of work therebetween and forming a portion of an induction loop, a core surrounding the side walls and the work-piece, and means for supplying alternating current to the induction loop to heat the piece and cause it to advance between the side walls; substantially as described.

2. In an induction heater, a pair of hollow side walls spaced apart to embrace and guide a piece of work therebetween and forming a portion of an induction loop, means for supplying cooling medium to the hollow side walls, a core surrounding the side walls and the work-piece, and means for supplying alternating current to the induction loop; substantially as described.

3. In an induction heater, a pair of hollow members spaced apart to embrace a piece of work and forming a portion of an induction loop, means for supplying cooling medium to the hollow members, a core surrounding the hollow members and having extensions carried close to the work-piece, and means for inducing alternating low voltage current in the hollow members; substantially as described.

4. In an induction heater, a pair of side walls spaced apart to embrace and guide a piece of work and forming a portion of an induction loop, a core surrounding the side walls and having core 45 projections substantially conforming to the work-piece, and means for supplying alternating current to the induction loop; substantially as described.

5. In an induction heater, a pair of side walls 50 spaced apart to embrace and guide a piece of work and forming a portion of an induction loop, a core of magnetic material surrounding the side walls, means for supplying alternating current to the induction loop, and means for cooling the side walls; substantially as described.

6. In an induction heater, a pair of side walls spaced apart to embrace a piece of work and forming a portion of an induction loop, a core surrounding the side walls and having projections 60 entering between the side walls and providing a gap for the work-piece, and means for supplying an alternating current to the induction loop; substantially as described.

7. In an induction heater, a pair of side walls 65 forming a portion of an induction loop, the side walls having extensions leaving a space substantially conforming to a piece of bar stock to guide the latter, a core surrounding the side walls and the bar, and means for supplying alternating current to the induction loop to heat the piece and cause it to advance endwise between the side walls; substantially as described.

8. In an induction heater, an inductor having a gap for a piece of work and composed of mate- 75

- rial which when heated produces a non-conducting oxide at the surface, the surfaces of the inductor at the gap conforming to the sides of the work to guide the latter endwise through the gap, 5 a core forming a magnetic linkage around the inductor and through the work-piece, and means for supplying alternating current to the inductor; substantially as described.
9. In an induction heater, an inductor having straight side walls arranged to closely embrace and guide a straight piece of work, a core forming a magnetic linkage around the inductor and through the work-piece, means for supplying alternating current to the inductor, and the side 10 walls next to the work having a self-oxidizing non-conducting lining; substantially as described.
10. In an induction heater, a core having a gap substantially conforming to a straight piece 15 of work, an inductor having a gap substantially conforming to the work-piece, the gap forming surfaces of the core and of the inductor substantially enclosing the work-piece on all sides, and means for supplying alternating current to 20 the inductor; substantially as described.
11. In a magnetic gap induction heater, an inductor having a pair of side walls to embrace and substantially conform to an elongated bar of magnetic material, a core having a gap substantially conforming to the bar, means for creating an alternating magnetic field at one portion of the bar to heat said portion of the bar to a temperature which decreases its permeability whereby the bar is caused to advance 25 between the side walls; substantially as described.
12. In an induction heater, a core having a gap for a piece of work, an inductor having straight side walls extending through the core and embracing and guiding the work, and the ends of the side walls being electrically connected; substantially as described. 5
13. In an induction heater, a core having a gap for a piece of work, an inductor having straight side walls extending through the core and guiding the work, a loop outside of the core 10 and having electrical connections with the side walls, and means for supplying alternating current to the loop; substantially as described.
14. In an induction heater, a core having a gap for a piece of work, an inductor having straight side walls extending through the core and guiding the work, legs connected to the side walls, and a loop connecting the legs; substantially as described. 15
15. In an induction heater, a core having a gap for a piece of work, an inductor having side walls extending through the core, a cross piece connecting the side walls at one end, and a loop having electrical connections with the side walls; substantially as described. 20
16. In an induction heater, a core, an inductor having side walls within the core and spaced apart to form a gap to receive a piece of work, a loop having electrical connections with the side walls, the loop and side walls being hollow to 25 circulate cooling fluid, and means for supplying alternating current to the loop; substantially as described. 30

GUSTAV FREDRICKSON. 35
